PHASE MODULATION RECEIVER

Murray G. Crosby, Riverhead, N. Y., assignor to
Radio Corporation of America, a corporation
of Delaware

Application October 30, 1941, Serial No. 417,103

14 Claims. (Cl. 250—20)

This application concerns a phase modulation receiver in which a frequency modulation converting circuit is utilized for detection and inverse feedback is applied in a manner which corrects the modulation on the incoming wave from phase modulation to modulation having the characteristics of frequency modulation. In order to do this, the frequency modulation receiver detector output is applied to a phase modulator associated with a preceding stage in a manner to phase modulate the wave supplied to the detector. This phase modulation may involve phase modulating oscillations used for heterodyning purposes in an incoming stage or may involve phase modulating the incoming signals in an amplifier through which the incoming signal passes.

My novel receiver then is of the type of phase modulation receivers wherein a frequency modulation detector is used to demodulate the modulated carrier and the frequency distortion encountered, due to the detection of phase modulation in a frequency modulation detector, is compensated for to produce an undistorted output. When a phase modulated carrier wave is received and impressed on a frequency modulation detector, the inherent difference between frequency modulation and phase modulation causes the output of the frequency modulation detector to have a frequency characteristic such that the output amplitude is proportional to the frequency of the modulating potentials. In order to correct for this characteristic, the receivers of the prior art have in some cases used correction circuits in the audio output or in the intermediate frequency circuits. In other systems such as, for example, that shown in Hansell U. S. Patent 2,207,541, the output of the frequency modulated wave demodulator working on the phase modulated wave is modified and fed back to frequency modulate the heterodyning oscillator. My receiver of the present disclosure uses the feed back potential to phase modulate the incoming wave. Another feature of my invention resides in a novel circuit arrangement wherein band pass filters and similar circuit elements causing time delay in the passed signals are excluded from the feed back loop circuit. In a modification the feed back potential is derived in a separate detector, thereby avoiding the defects caused in known receivers of this type by time delay in the feed back circuits.

In describing my invention in detail, reference will be made to the attached drawings wherein

Fig. 1 illustrates an embodiment of my receiver, in which heterodyning oscillations are modulated

as to phase by potentials derived by demodulating phase modulated waves in a frequency modulated receiver and the so phase modulated oscillations used to heterodyne the received wave to a frequency commensurate with the tuning of the frequency modulation detector;

Figure 1a is a graph illustrating the manner in which the correction is accomplished in the receiver of Fig. 1. This figure also illustrates the 10 manner in which the correction is accomplished in the remaining figures;

Figs. 2, 3, 4, and 5 are modifications of the arrangement of Fig. 1.

In Figs. 3, 4, and 5 a separate frequency modulator 15 detector is used for obtaining the control potential and the control potential is modified and operates through a reactance tube on an oscillator to modulate its frequency in a sense to compensate the output of a frequency modulation 20 detector operating on phase modulated waves. In this arrangement, since a separate detector is used to derive the feedback potential, the correction may be accomplished in an early stage of the receiver with bandpass filters following the same 25 without including such filters in the degeneration circuit to cause oscillations therein.

The circuit of Fig. 1 is a fundamental circuit. The signal applied to the input of network 1 is 30 amplified and converted therein to intermediate frequency. Network 1 schematically represents a conventional radio frequency amplifier and first detector, it being understood that the latter is fed with local oscillations from a local high frequency oscillator whereby the output energy of 35 the first detector is of intermediate frequency (I. F.). The intermediate frequency energy is selectively amplified in band pass I. F. amplifier 2, and fed to heterodyne converter 3, where it 40 is again converted in frequency and supplied to a frequency modulation demodulator consisting of a discriminator and detector circuit. Beating oscillator 6 feeds its energy through phase modulator 5 and frequency multiplier 4 to the heterodyne and converter 3. The second intermediate 45 frequency output of heterodyne converter 3 is fed to the frequency discriminating circuit comprising a transformer 7 and coupling condenser 8 which converts the frequency modulations on the 50 wave energy fed thereto to amplitude modulation for detection by detectors 9 and 10. The phase modulator 5 may be of any known type, as, for example, my U. S. Patent No. 2,033,231 granted March 10, 1936. Since such circuits are 55 well known in the art and since this circuit per-

se forms no part of my invention, the same need not be described here.

The frequency modulation detector circuit comprising paths 7 and 8 and opposed detectors 9 and 10, is likewise of a well known type shown by S. W. Seeley in his U. S. Patent No. 2,121,103 granted June 21, 1938, and per se forms no part of my present invention and a description thereof is believed unnecessary. However, it will be noted that at the output of the detectors 9 and 10, that is, across resistances R and R₁ connected in series between the cathode of detector 9 and ground, will appear potentials characteristic of the phase modulations on the wave energy being detected, except for the modification thereof referred to above and referred to hereinafter. These potentials may be fed to audio frequency amplifiers, and are utilizing means and also fed through line 11 to the phase modulator 5 to control therein the phase of the oscillations from oscillator 6.

With the phase modulated signal applied to the input of the receiver at network 1, the output of the receiver across the resistance R and R₁, if line 11 were omitted from the circuit of Fig. 1, would have a characteristic as shown by the solid line audio frequency v. output characteristic A in Fig. 1a. The polarity of the phase modulation applied to the beating oscillations from 6 by phase modulator 5 is made such as to reduce the degree of phase modulation on the frequency converted output of the heterodyne converter 3 when the audio potentials from line 11 are applied to phase modulator 5. Thus the modulating potentials applied to "unmodulate" or lessen the degree of modulation on the second intermediate frequency tend to reduce the degree of modulation to a larger extent on a higher modulation frequency by virtue of the fact that the potential applied to line 11 has a characteristic as shown by the solid line A of Fig. 1a. Consequently, the feedback, due to line 11, tends to flatten out the frequency characteristic at the output of the detectors 9 and 10 so that they have a characteristic as shown by the dotted line B of Fig. 1a. Thus the distortion due to the fact that a frequency modulated wave detecting system is used on a phase modulated wave is automatically corrected for.

Frequency multiplier 4 of Fig. 1 is inserted for the purpose of increasing the degree of phase modulation produced by phase modulator 5. Oscillator 6 is tuned to a frequency which is less than the beat frequency desired by the ratio of the frequency multiplier employed in 4.

An alternative to the application of the feedback phase modulation to the beating oscillator is to pass the phase modulated waves through a phase modulator in an intermediate frequency stage. This in effect eliminates units 3, 4, and 6, and includes the phase modulator 5' at the position where 3 is now shown in Fig. 1. Thus the step of frequency conversion is eliminated and phase modulation is applied directly to the phase modulated carrier of intermediate frequency. Such an arrangement has been shown in Fig. 2 of the drawings. The operation of Fig. 2 of the drawings is similar to the operation of the arrangement of Fig. 1, modified, however, as described above. In Fig. 2 the discriminator circuit 7, 8 and detectors 9 and 10 are now operating at the first intermediate frequency and are tuned in accordance therewith.

In the circuit of Fig. 3 the feedback potentials are obtained in a separate receiver and sup-

plied to a receiver, which herein will be designated the main receiver, for control purposes to condition the said main receiver, which is of the frequency modulated wave type, to the reception of phase modulated waves. This arrangement has the advantage that there are no time delays in the feedback circuit which can cause regeneration or sustained oscillations in either receiver. The receiver comprises a radio amplifier 40 feeding amplified wave energy to two heterodyning detector systems, the first of which comprises oscillator 41 and detector 42, and the second of which comprises oscillator 47 and detector 49. The output of detector 42 supplies energy of intermediate frequency to a band-pass intermediate frequency amplifier 43, and from 43 the filtered and intermediate frequency phase modulated wave energy is supplied to a discriminator circuit 44 and thence to detectors 45 and 46 to provide a control potential on line 11 as in Fig. 1. This control potential is supplied by way of a potential modifying time constant circuit including condenser 44 and resistance 45 to so modify the potentials that the frequency modulator consisting of the reactance tube modulator 48 and oscillator 47 feeds a phase modulated wave to detector 49. The modulated oscillations are used in detector 49 to heterodyne the phase modulated wave to a lower frequency in 50 and supply the same to the second frequency discriminator circuit 51 of the main receiver, and from the discriminator 51 to detectors 52 and 53, from whence the output may be supplied to audio frequency amplifiers at utilization means.

It is to be noted that the band-pass filter 50 inserted between heterodyne detector 49 and the frequency discriminator 51 of the main receiver is not included in the feedback circuit and therefore cannot introduce time delay to cause regeneration or sustained oscillations. Furthermore, the same can be said of the band-pass filter and amplifier 43 of the receiver for obtaining the control potentials. The first beating oscillator of the circuit of Fig. 1 could not be controlled, since the band-pass filter would be inserted between the detector 3 and the discriminator 7, 8 and would introduce a time delay which limits the degree of feedback which can be used before sustained oscillations are encountered.

In the arrangement of Fig. 3 the beating oscillator 47 is phase modulated by corrected frequency modulation. By this is meant that the potentials supplied to the reactance tube 48 are so modified by condenser 44 and resistance 45 that although the reactance tube 48 modulates the frequency of oscillator 47, the resultant modulated oscillations have the characteristics of phase modulation. Condenser 44 is adjusted so that its audio reactance is high compared to resistance 45 so that the network imparts an attenuation to the lower frequencies thereby causing the output of the network to have an amplitude proportional to the frequency of the input. This is the desired characteristic for changing frequency modulation into phase modulation.

The arrangement of Fig. 3 may be modified as illustrated in Fig. 4 to phase modulate the oscillations for oscillator 47' in 47'' and supply them by way of a frequency multiplier 47''' to the heterodyning detector 49. The operation of this arrangement would be as described in connection with Fig. 1 of the drawings.

The arrangement of Fig. 3 may also be modi-

fied as illustrated in Fig. 5 so that the phase modulated wave energy is supplied to a converter comprising oscillator 41 and detector 42, as in Fig. 5, and to a phase modulator 5'', as in Fig. 2. The potentials derived from the output of the detectors 45 and 46 are then used to modulate the phase modulated wave energy supplied by way of the phase modulator 5'' to the band-pass filter and intermediate frequency amplifier 50. The operation here is as described hereinbefore in connection with Figs. 1 and 2, and a detailed description thereof is not thought necessary herein.

In circuit arrangements of the type involved the feed-back heretofore has been applied to the high-frequency oscillator instead of to a second intermediate frequency oscillator so that too much time delay is introduced by the band-pass intermediate-frequency amplifier. This reduces the amount of feedback possible so that little or no frequency correction may be obtained. With the time delay in the circuit, together with the 90 degree phase lag imposed by the inductance-resistance correcting circuit, the amount of feedback allowable without encountering sustained oscillation is small so that the overall correction from the frequency to phase modulation is small. In my arrangement, as illustrated in Fig. 1, there are no filter circuits or circuits of a similar nature in a feedback circuit. The discriminator circuit is coupled directly to the converter associated with the modulated heterodyning oscillations. In the arrangement of Figs. 3, 4, and 5, separate paths are used so that here again the filter circuits of the receiver are not included in the feedback path.

What is claimed is:

1. The method of demodulating phase modulated wave energy which includes the steps of demodulating said wave energy to obtain modulation potentials which are modified in accordance with their frequency and therefore do not correctly represent the modulations on said wave energy, and phase modulating the said wave energy in accordance with said demodulated potentials to cause said modulation potentials to correspond substantially to said wave modulations.

2. The method of demodulating phase modulated wave energy which includes the steps of beating said wave energy with oscillatory energy to obtain wave energy of lower frequency, demodulating said wave energy of lower frequency to obtain modulation potentials which are modified in accordance with their frequency and do not correctly represent the modulations on said wave energy, and phase modulating the oscillatory energy used in said beating process with said potentials to cause said modulation potentials to correspond substantially to said wave modulations.

3. In means for demodulating phase modulated wave energy, a frequency modulated wave detector having an input and an output, a phase modulator having an input and having an output coupled substantially directly to said frequency modulated wave detector input, a coupling between the output of said frequency modulated wave detector and said phase modulator, and means for impressing phase modulated energy on said phase modulator input.

4. In means for receiving phase modulated wave energy, a frequency modulated wave detector having an input and an output, a heterodyne detector having an output coupled sub-

stantially directly to said frequency modulated wave detector, a source of oscillations, a phase modulator coupling said source of oscillations to said heterodyne detector, a coupling between the output of said frequency modulated wave detector and said phase modulator, and means for impressing phase modulated energy on said heterodyne detector.

5. In a phase modulation receiver, a frequency modulated wave detector, a frequency converting system, having an input excited by said wave energy, and by locally generated oscillations, said converting system having an output coupled to said frequency modulated wave detector, and means for phase modulating the oscillations impressed on said converting system in accordance with the output of said frequency modulation detector.

6. In a phase modulation receiver, a frequency modulated wave detector, a frequency converting system having an input excited by said wave energy, an oscillator for generating oscillations, said converting system having an output coupled to said frequency modulated wave detector, connections for phase modulating the generated oscillations in accordance with the output of said frequency modulation detector, and connections for multiplying the frequency of the phase modulated generated oscillations and impressing them on said converting system.

7. In a wave length modulation system, a source of wave length modulated wave energy, a wave length modulated wave detector, connections for deriving potentials representative of the wave length modulations on said wave energy, connections for additionally modulating the length of said wave energy in accordance with said derived potentials, and additional connections for impressing said additionally modulated wave energy on said detector.

8. In a phase modulation system, a pair of frequency modulated wave detectors, connections for impressing phase modulated waves on both of said detectors, and connections for additionally wave length modulating the waves impressed on one of said detectors in accordance with potentials derived from the output of the other of said detectors.

9. In a phase modulation receiver, a pair of frequency modulated wave detectors, a pair of heterodyne detectors including local oscillators for converting the phase modulated wave energy to correspondingly modulated wave energy of lower frequency, connections between the heterodyne detectors and the frequency modulated wave detectors for impressing the said wave energy of lower frequency on said frequency modulation detectors, and connections between one of said frequency modulated wave detectors and one of said local oscillators for modulating the phase of the oscillations generated by said one of said local oscillators in accordance with the output of said one of said frequency modulated wave detectors.

10. The method of deriving the modulation potentials from wave energy the phase of which has been modulated in accordance with said modulation potentials which includes the following steps, demodulating said phase modulated wave energy to obtain therefrom modulation potentials which are modified in accordance with their frequency and, therefore, do not correctly represent the modulations on said wave energy, and additionally modulating the phase of said wave energy in accordance with said derived po-

tentials to cause said derived potentials to correspond substantially fully with the modulations used to phase modulate said wave energy.

11. The method of deriving the modulation potentials from wave energy the phase of which has been modulated in accordance with said modulation potentials which includes the following steps, demodulating said phase modulated wave energy to obtain therefrom modulation potentials which are modified in accordance with their frequency and, therefore, do not correctly represent the modulations on said wave energy, additionally modulating the phase of said wave energy in accordance with said derived potentials, and demodulating said additionally phase modulated wave energy to derive potentials which correspond substantially fully with the modulations used to phase modulate said first mentioned wave energy.

12. In apparatus of the class described, a converter circuit having an input whereon phase modulated wave energy is impressed, said converter circuit having an output, a frequency modulated wave detector having an input coupled to said converter and having an output from which the detected signal may be derived, a source of local oscillations, a phase modulator and a frequency multiplier in cascade coupling said source of oscillations to said converter, and a connection between the output of said detector and said phase modulator for modulating the oscillations therein in accordance with the output of the detector.

13. In apparatus of the class described, a first mixer stage having an input on which phase modulated energy to be demodulated is impressed, a first source of oscillations coupled to said mixer stage, said mixer stage having an output, an intermediate frequency amplifier having an input coupled to the output of said first mixer stage, said intermediate amplifier output having an output, a first frequency modulated wave detector having an input coupled to the output of

said amplifier, said detector having an output, a second mixer stage having an input excited by said phase modulated wave energy, a second source of oscillations coupled to said second mixer stage, said second mixer stage having an output, a second intermediate frequency amplifier having an input coupled to the output of said second mixer stage, said second amplifier having an output, a second frequency modulated wave detector having an input coupled to the output of said second amplifier, said second detector having an output from which the signal modulations may be derived, and a coupling between the output of said first frequency modulation detector and said second oscillator for modulating the phase of the oscillations generated by said second oscillator in accordance with the output of said first detector.

14. In apparatus of the class described, a first converter stage having an input excited by phase modulated wave energy to be demodulated, a source of oscillations coupled to said first converter, said first converter having an output, an amplifier having an input coupled to the output of said first converter, said amplifier having an output, a first frequency modulated wave detector having an output and having an input coupled to the output of said amplifier, a second converter having an input excited by said phase modulated wave energy, a second source of oscillations, a phase modulator and a frequency multiplier connected in the order recited for supplying beating oscillations to said second converter, a coupling between said phase modulator and the output of said first detector for modulating the phase of the oscillations from said second source in accordance with the output of said first detector, and a second frequency modulated wave detector having an input coupled to said second converter and having an output from which the modulation may be derived.

MURRAY G. CROSBY.
